2,054,980

ELECTROMAGNETIC PHONOGRAPH RECORDER

Manfred J. Johnson, Naugatuck, Conn., assignor to Dictaphone Corporation, Bridgeport, Conn., a corporation of New York

Application September 19, 1927, Serial No. 220,574
Renewed August 5, 1935

23 Claims. (Cl. 179—100.41)

This invention relates to improvements in systems for translating or converting electrical impulses into mechanical movements, and to improved means employed in such systems. In 5 a more specific aspect, the present invention is concerned with recording sounds electrically.

The recording mechanism herein disclosed is of the type employing an electromagnet field and a separately energized or electrically controlled armature, the armature being connected to an air disturbing member such as a diaphragm or to a stylus adapted to record on a record blank. In order that the armature may have sufficient amplitude movement to produce results under more or less adverse conditions, the 10 electric recorder has interposed between it and the sound sensitive device such as a microphone, a thermionic amplifier. This, briefly stated, refers to the systems disclosed herein but, so far as some of the features of the present invention 15 are concerned, namely the improved construction of the electrical recorder from a mechanical point of view, the present invention is not limited to electrical translating units used merely in 20 this particular system.

An important feature of this invention is the provision of an electrical recorder having a field magnetizing coil supplied by a source of current used in an amplifying circuit connected with 25 the recorder.

And a further and co-related feature is the arrangement of the field magnetizing coil so that it will act to by-pass the direct-current component, of the current fed to the recorder, 30 around the armature actuating coil to prevent any tendency of the armature to become permanently magnetized or biased toward one polarity, and yet so that it will not pass voice-currents but will force the latter to flow through the 35 actuating coil.

It will thus be seen that, according to the present invention, a single coil is arranged to function both as a voice-frequency choke coil, and also as a magnetizing coil for the field of 40 the device. This arrangement naturally tends to reduce the cost of the device and gives remarkable results.

Another feature of the present invention is the provision of improved mounting means for the 45 armature and improved means for damping the oscillations of the armature so as to bring the amplitude of the vibrations within proper limits for the successful functioning of the device.

Other features and advantages will hereinafter 50 appear.

In the accompanying drawings—

Figure 1 is a side view, partly in section, of a phonograph showing the recording mechanism of the present invention applied thereto.

Fig. 2 is a front elevation of the electrical 5 recorder of the present invention with a protecting cover therefor shown in section.

Fig. 3 is a sectional view of the electrical recorder taken for the most part on the line 3—3 of Fig. 2.

Fig. 4 is a plan view of the electrical recorder showing the cover removed.

Fig. 5 is a disassembled perspective view showing some of the component parts of the electric recorder.

Fig. 6 is a diagrammatic view showing a system, according to the present invention, employing the electrical recorder shown in Figs. 1 to 5.

The phonograph shown in the accompanying drawings comprises a base 10 on which is supported for rotary movement a mandrel 11 for a sound-record 12 over which moves a carriage 13 under the influence of a feed-screw 14 driven concomitantly with the mandrel 11 and engaged by a feed-nut 15 on the carriage. The carriage 20 usually supports a sound-box for recording and/or reproducing on a record blank or record, and has a socket 16 for receiving the sound-box.

In the present case, however, there is substituted for the usual sound-box, a sound-box 30 made in accordance with the present invention and comprising means for electrically recording desired sounds. This electric recorder, indicated generally by the reference numeral 17, comprises a base 18 in the form of a disk adapted to fit 35 in the socket 16 of the carriage 13. Pivotaly mounted on a bracket carried by the base 18 is a lever 19 pivotally supporting at 20 a stylus lever 21 which is a first-class lever having at one end a stylus 22 and at the other end pivotal 40 connection with an actuating link or rod 23. The pivotal mounting of the lever 19 is provided, as usual, to permit the stylus to be raised clear of the record blank by manipulation of a lever 24, also to permit gradual rise and fall of the 45 stylus in accommodating itself to eccentricities of the record surface while the record is rotating, and also to accommodate itself to records of different thicknesses or diameters.

The stylus 22 is caused to vibrate so as to cut 50 undulating helical grooves in the record surface corresponding to sound vibrations by movements transmitted to it through the link 23 and armature 25 adapted to be controlled by an actuating coil 26. The relation between the actuating coil 55

26 and the armature is substantially the same as that disclosed in the patent to Capps, No. 441,396, dated Nov. 25, 1890, and accordingly, the actuating coil has a central passage 27 through 5 which the armature extends when the armature is placed in a magnetic circuit comprising pole-pieces 28 having pole-tips 29 and 30, the magnetic flux flowing through said magnetic circuit being supplied by a permanent magnet or by a 10 magnetizing coil.

According to the present invention, the pole-pieces 28 are secured together so as to each be the proper distance from the armature by means of a bridge plate 31 having holes 32 through 15 which screws 33 pass and enter tapped holes in the pole-pieces 28. The bridge plate 31 is made of non-ferrous material and forms no part of the magnetic circuit. The bridge plate 31 has an aperture 34 through which the armature 25 20 extends. In order that it may be conveniently adjusted in its assembly so that it will lie midway between the pole-tips 29 and 30 of each of the poles 28, the armature is mounted on the outside face of the bridge plate 31. This mounting 25 comprises a strip 35 of resilient material to which the end of the armature is riveted as at 36. The armature mounting strip 35 extends transversely with relation to the armature and at each of its ends is provided with elongated 30 slots 37 through which mounting screws 38 pass, see Fig. 2. These screws 38 are threaded in the plate 31 and when loosened permit movement of the armature in the direction of the pole-tips 29 and 30 in the gap between the latter. When 35 the armature is properly positioned in the gap, the screws 38 are tightened to securely hold the armature in the desired position. The mounting strip 35 is cut-away at 39 so as to decrease its resistance to torsional movement to that just 40 sufficient to maintain the armature in normal position in the magnetic circuit. The armature being fulcrumed at one end on the supporting strip 35 is provided at its other end, which protrudes beyond the pole-pieces 28, with a connection 40 to the link 23 which is connected with the stylus lever 21.

In order to keep the amplitude of vibrations of the armature 25 within proper limits for the 50 successful operation of the device, making it a periodic, the present invention provides damping means operative upon the free end of the armature at a point adjacent its connection 40 to the link 23. This damping device, according to the present invention, comprises a pair of blocks 41 of rubber or other resilient material which 55 are placed at opposite sides of the armature. These blocks 41 are held in operative position by angular pressure plates 42, one side of each of which is provided with an elongated slot 43 for the reception of a screw 44 threaded in the 60 related pole-pieces 28. In assembling and adjusting the device, the screws 44 are loosened and the pressure plates 42 are forcefully brought together so that they press with considerable 65 force upon the armature and so that they press with equal force and permit the armature to maintain its centralized position in the gap between the facing pole-pieces 28. Movement of the pressure plates 42 for this purpose is permitted by the elongated slot 43 therein. When 70 the plates have been properly adjusted and the rubber blocks 41 are under tension and in proper position, the screws 44 are tightened to prevent accidental or unintentional movement thereof. 75 Preferably, composition of the blocks 41 is such

that when the blocks are pressed against the armature with sufficient force, the side margins of the blocks touch each other, as shown in Fig. 1, at both sides of the armature. Hence, the armature is confined entirely by the rubber 5 blocks which then act as though the armature were inserted in a single block of rubber, which, however, is under tension.

If desired, the pole-pieces 28 may be held more rigidly by the addition of a U-shaped non-ferrous plate 45, one secured to each side of the two blocks 28 by screws 46, see Fig. 1.

As stated above, magnetic flux applied to the pole-pieces 28 may be supplied, so far as some of the aspects of the present invention are concerned, from a permanent magnet or from an electromagnet having a magnetizing coil. It is preferred, for reasons hereinafter given, to supply the magnetic flux by means of a magnetizing coil 47 having a central aperture 48 through 20 which a leg 49 of an angular field-piece 50 passes. The angular field 50 is screwed to the lower block 28, see Fig. 5, and then extends rearwardly where it is provided with the leg 49 which passes through the energizing coil 47. 25 After the coil is placed on the leg 49, another arm 51 of the field-piece is secured to the leg 49 by screws 52 and holds the coil 47 in operative position. The forward end of the arm 51 contacts with the upper pole-pieces 28 to which 30 it is secured by screws 53. Thus, it will be seen that, there is provided a magnetic circuit including the lower pole-piece 28, field-piece 50 having the leg 49, and arm 51, and the upper pole-piece 28, in the gap of which is located the 35 armature 25.

Preferably, in manufacturing the device, first the pole-pieces are secured to the bridge plate 31, then the armature is put in position and adjusted, the field is then completed by assembling field-piece 50 and the field-piece arm 51 after placing the magnetizing coil 47 on the leg 49, then the assemblage is secured to the base 18 by screws 54 (as shown in Fig. 3) and then the link 23 is passed through a clearance opening 55 in the field-piece 50, and finally the ends of the link are connected to the armature 25 and stylus lever 21.

The entire device may be enclosed by a cover 56 secured to posts 57 carried by the base 18, 50 and the cover may have an opening 58 through which the wires leading to the unit may pass.

Referring now to Fig. 6, which shows a system employing the electrical recorder of the present invention, sound from its original source 55 impinges upon the microphone or the pick-up device 59 having a local battery 60 in series with it and in series with primary 61 of an induction or coupling coil. The secondary 62 of the induction coil may, of course, be connected 60 directly to the electrical recorder if so desired. However, in order that sounds which are feeble at the source may be recorded, it is preferable that the induction coil be connected at one side by a wire 63 to the grid 64 of a thermionic 65 amplifier 65, whose filament or heating member 66 is connected by wires 67 and 68 to a negative-bias battery C and from the latter by a wire 69 to the other side of the secondary 62. The filament, as usual, is connected by a wire 70 to a source A of current supply therefor which is connected by a wire 71 to a rheostat 72 connected by a wire 73 to the wires 67 and 68. The plate 74 of the thermionic device 65 is connected by a wire 75 to the electric recorder, the latter is 75

connected by a wire 76 to a source of plate voltage supply B which in turn is connected by a wire 77 to the wire 67 leading to the filament.

So far as some aspects of the present invention are concerned, the magnetizing coil 47 may be energized by any suitable source of current, for instance, by the source A for the filament.

However, according to the present invention, the magnetizing coil 47 is energized to cause magnetic flux to flow through the magnetic circuit comprising the field-pieces 50 and pole-pieces 28 by the direct-current component of the current flowing through the plate circuit of the thermionic device. This circuit includes the

plate 74, the wire 75, the wire 76, source of current supply B, the wire 77, wire 67, and the space between the filament 66 and the plate 74. Accordingly, the coil 47 is connected by a wire 78 directly to the wire 75 leading to the plate

74 and by a wire 79 directly to the wire 76 leading to the source of current B. Since the direct-current component of the current passing through the plate circuit is usually high, the winding of the coil 47 is adapted for this current, and this winding and the field-pieces 50 and 51 are so proportioned that the impedance of the coil 47 to voice-currents is so high that the voice-currents pass through a course of less resistance and ultimately to the actuating coil

26. For this purpose, the actuating coil 26 is connected by a wire 80 to the wire 76 leading to the source of current-supply B and the other side of the coil 26 is connected by a wire 81 to one side of a condenser 82, the other side of

which is connected by a wire 83 to the wire 75 leading to the plate 74. Consequently, the voice-currents find an easy path through the condenser and through the actuating coil back to the source of current-supply B, and because of the interposition of the condenser 82 between the plate 74 and the actuating coil 26, the direct-current component of the currents flowing through the plate circuit cannot pass to the actuating coil 26, and hence pass through the coil 47 and cause the latter to magnetize the field-piece 50 and the pole-pieces 28. Thus, it will be seen that the present invention provides a single coil which acts both as a choke coil to prevent the direct-current component of the current flowing through the plate circuit from

permanently magnetizing the armature or biasing the armature toward one polarity, and to magnetize the field piece for the electrical recording unit.

55 The condenser 82, described in connection with the system shown in Fig. 6, may, of course, be located in proximity to the thermionic amplifying device. However, it is preferable that the condenser be associated with the electrical recording unit and is so shown in Figs. 1 to 4, in which the condenser 82 is secured to a fibre plate 83 by screws 84, the plate being secured to the arm 51 of the field 50 by a screw 85. When the condenser is so located, a further advantageous result is obtained, for then only two wires—namely wires 75 and 76—need be brought to the electrical recording unit through the opening 58 of the cover therefor. Thus, instead of having a cable of three or more wires, which would be necessary in the event that an auxiliary source of current were utilized to magnetize the field, the present invention provides only two wires 75 and 76. This is an important factor since the carriage, as above stated, travels from side to side and any bulky cable which might be used

would retard travel of the carriage and soon become worn due to friction.

Variations and modifications may be made within the scope of this invention and portions of the improvements may be used without others.

Having thus described the invention, what is claimed as new and for which it is desired to obtain Letters Patent, is:

1. A translating device comprising a magnetic field-piece; pole-pieces secured thereto in juxtaposition; a bridge plate of non-magnetic material structurally connecting the pole-pieces; an armature disposed between and extending outwardly beyond said pole-pieces; an energizing coil for said armature disposed between said pole-pieces and means for mounting the armature on the bridge plate for oscillatory movement said means being connected to one end of said armature.

2. A translating device comprising a magnetic field-piece; pole-pieces secured thereto in juxtaposition; a bridge plate of non-magnetic material structurally connecting the pole-pieces; an armature disposed between and extending outwardly beyond said pole-pieces; and means for adjustably mounting the armature on the bridge plate for oscillatory movement.

3. A translating device comprising a magnetic field-piece; pole-pieces secured thereto in juxtaposition; a bridge plate of non-magnetic material structurally connecting the pole-pieces; an armature disposed between and extending outwardly beyond said pole-pieces; and a spring member riveted to the end of said armature and secured to said bridge plate for permitting oscillatory movement of said armature about the axis of said spring member.

4. A translating device comprising a magnetic field-piece; pole-pieces secured thereto in juxtaposition; an armature disposed between said pole-pieces and extending outwardly beyond said pole-pieces; an armature energizing coil mounted between said pole-pieces; and means supported at adjacent ends of said juxtaposed pole-pieces and adapted to engage the portion of the armature extending beyond the pole-pieces to damp the vibratory movements of the armature, said means being each adjustable to permit the effect of each damping means to be varied at will.

5. A translating device comprising a magnetic field-piece; pole-pieces secured thereto in juxtaposition; an armature disposed between said pole-pieces and extending outwardly beyond the pole-pieces; a bracket carried by each pole-piece and disposed adjacent the portion of the armature extending beyond the pole-pieces; and blocks of resilient material interposed between the armature and the brackets.

6. A translating device comprising a magnetic field-piece; pole-pieces secured thereto in juxtaposition; an armature disposed between said pole-pieces and extending outwardly beyond the pole-pieces; an angle plate secured to each of the juxtaposed pole-pieces and extending over that portion of the armature which extends beyond the pole-pieces; and means interposed between said angle plate and said armature to damp the vibration of the armature.

7. A translating device comprising a magnetic field-piece; pole-pieces secured thereto in juxtaposition; a bridge-plate of non-magnetic material structurally connecting the pole-pieces; an armature disposed between said pole-pieces and

extending outwardly beyond the pole-pieces; and a spring member having one end of said armature secured thereto, said spring member being secured to said bridge-plate to permit 5 oscillatory movement of said armature about an axis of said spring member.

8. A translating device comprising a magnetic field-piece; recessed pole-pieces secured thereto in juxtaposition; an armature comprising a magnetizable bar extending between and beyond 10 said pole-pieces; a support for said armature; resilient means for securing an end of said armature to said support to permit oscillation of said armature between said pole-pieces; an 15 energizing coil for said armature mounted within the recesses of the pole-pieces, and an energizing coil for said field-piece.

9. A translating device comprising a magnetic field-piece; recessed pole-pieces secured thereto 20 in juxtaposition; an armature comprising a magnetizable bar extending between and beyond said pole-pieces; a support for said armature; resilient means for securing an end of said armature to said support to permit oscillation of 25 said armature between said pole-pieces; an energizing coil for said armature mounted within the recesses of the pole-pieces; an energizing coil for said field-piece; and means supported at 30 adjacent ends of said pole-pieces and adapted 35 to engage a portion of the armature to damp the vibratory movements thereof.

10. A translating device comprising a magnetic field-piece; pole-pieces secured thereto in juxtaposition; a bridge plate of non-magnetic material 40 structurally connecting the pole-pieces; an armature disposed between said pole-pieces and extending outwardly beyond the bridge plate; means for adjustably mounting the armature on the bridge plate for oscillatory movement; and means supported on adjacent ends of said 45 pole-pieces and adapted to engage the portion of the armature extending beyond the pole-pieces to damp the vibratory movements of the armature, said means being each adjustable to permit the effect of each damping means to be varied at will.

11. An electrical sound recorder comprising, in combination, a frame, a floating support pivotally mounted on said frame, a lever arm pivotally mounted for oscillation on said floating support, a stylus mounted on one end of said arm, a link pivotally secured to the other end of said arm, a magnetic driving motor mounted on said frame and comprising a vibratile armature biased to neutral position, and electromagnetic means for positively actuating said armature in either direction, and a connection between said armature and said link.

12. An electrical sound recorder comprising, in combination, a frame, a magnet support secured to said frame, a magnetic driving motor positioned on said frame, said motor comprising a vibratile armature, spring-biased to neutral position, and electromagnetic means for positively actuating said armature in either direction from neutral, a floating support pivotally secured to said frame, a lever mounted for oscillation thereon, a stylus mounted on one end of said lever, and a link pivotally connected on one 70 end to the other end of said lever, and connected at the other end to said armature.

13. An electrical sound recorder comprising, in combination, a frame, a magnetic driving motor positioned on said frame, said motor comprising a vibratile armature, a spring for supporting

said armature in neutral position, and electromagnetic means for positively actuating said armature in either direction from neutral position, a floating support pivotally secured to said frame, a lever mounted for oscillation thereon, 5 a stylus on one end of said lever, and a rigid link pivotally connected between one end of said armature and the end of said lever opposite said stylus, said link being so arranged as to positively drive said stylus in either direction of 10 movement.

14. An electrical sound recorder comprising, in combination, a frame, a magnetic driving motor positioned on said frame, said motor comprising a magnet having pole-pieces extending toward 15 each other, and each having projecting portions at each end defining a winding-receiving space, a winding therein, an armature positioned between said pole-pieces and interlinking said winding, a spring for supporting said armature 20 in neutral position for oscillation, and damping means interposed between said armature and said pole-pieces at the point of maximum vibration amplitude of said armature.

15. An electrical sound recorder comprising, in combination, a frame, a floating support pivotally mounted on said frame, a lever arm pivotally mounted for oscillation on said floating support, a stylus mounted on one end of said arm, a link pivotally secured to the other end of said arm, a magnetic driving motor mounted on said frame and comprising a vibratile armature biased to neutral position, a magnet having pole-pieces defining a pair of air gaps at opposite 30 ends of said armature, a coil surrounding said 35 armature, and a connection between said link and said armature in the plane of said air gaps.

16. An electrical sound recorder comprising, in combination, a frame, a floating support pivotally mounted on said frame, a lever arm pivotally mounted for oscillation on said floating support about an axis parallel to the axis of said support but offset therefrom, a stylus mounted on the end of said lever arm remote from the axis of said support, a magnetic driving motor mounted on said frame and comprising a magnet having a pair of pole-pieces defining an air gap, an armature of magnetic material mounted for vibration within said air gap, and a connection between said armature and the free end of 40 said lever arm. 45

17. An electrical sound reproducer comprising, in combination, a frame, a floating support pivotally mounted on said frame, a lever arm pivotally mounted for oscillation on said floating support, a stylus mounted on one end of said arm, and means for converting movements of said stylus into electrical currents, comprising a magnet having pole-pieces defining a plurality of air gaps, an armature positioned within said 55 gaps for vibration therein, a coil surrounding said armature, and a connection between the free end of said lever arm and said armature.

18. An electrical sound reproducer comprising, in combination, a frame, a floating support pivotally mounted on said frame, a lever arm pivotally mounted for oscillation on said floating support about an axis parallel to the axis of said support but offset therefrom, a stylus mounted on one end of said lever, and means for converting movements of said stylus into electrical currents, comprising a magnet having pole-pieces defining a pair of air gaps, an armature biased to neutral position and mounted for vibration within said gaps, and a connection be- 60 65 70 75

tween the free end of said lever arm and said armature.

19. An electro-mechanical translating device comprising, in combination, a frame, a floating support pivotally mounted on said frame, a lever arm pivotally mounted on said support for oscillation thereon, a stylus mounted on one end of said arm, a magnet mounted on said frame, pole-pieces defining an air gap mounted on said

10 magnet, an armature mounted for vibration in said gap and biased to neutral position, and a connection between said lever and said armature.

20. An electro-mechanical translating device comprising, in combination, a frame, a floating support pivotally mounted below said frame, a lever arm pivotally mounted on said support for oscillation thereon, a stylus mounted on one end of said arm, a magnet mounted on said frame, pole-pieces defining a pair of air gaps mounted

15 on said magnet, an armature mounted for vibration in said air gaps, resilient damping means surrounding a portion of said armature, and a connection between said lever and said armature.

25 21. An electro-mechanical translating device comprising, in combination, a frame, a floating support pivotally mounted below said frame, a lever arm pivotally mounted on said support for

oscillation thereon, a stylus mounted on one end of said arm, a magnet mounted on said frame, pole-pieces defining a pair of air gaps mounted on said magnet, an armature mounted for vibration in said air gaps, resilient damping means surrounding a portion of said armature, and a connection between said lever and said armature at a point outside the portion thereof included between said air gaps. 5

22. A translating device comprising a magnetic field-piece; pole-pieces secured thereto in juxtaposition; an armature disposed between said pole-pieces; an energizing coil for said armature disposed between said pole-pieces; and torsional means connected to one end of said 10 armature for supporting the armature in position for oscillatory movement between the pole-pieces.

23. A translating device comprising a magnetic field-piece; pole-pieces secured thereto in 20 juxtaposition; an armature comprising a magnetizable bar extending between and beyond said pole-pieces; an energizing coil for said armature mounted between the pole-pieces; and resilient means secured to an end of said armature and 25 mounted to retain said armature in position to oscillate between said pole-pieces.

MANFRED J. JOHNSON.
